ZIPPED-IN UNDERARM GUSSET

William T. Previdi, Allendale, N. J.

Application January 15, 1947, Serial No. 722,163

1 Claim. (Cl. 2—125)

1

This invention relates to garments such as sport shirts, work clothes, and the like, and more particularly to the construction of the same between a limb and body part as within the arm-pits.

It is an object of the present invention to provide a sport shirt, flier's air suit, a piece of work clothing or the like, with an armpit gusset so associated and combined with the remainder of the garment that great freedom of movement will be allowed to the wearer without any likelihood of tearing, ripping or other damage or injury to the cloth beneath and adjacent the arm-pits or elsewhere on the garment as a consequence of overactivity by the wearer.

It is another object of the invention to provide an underarm gusset construction which may be zipped in by a "zipper" running along under the arm at times when the garment is to be worn under other clothing and when there is no anticipation that athletic or other added activity requiring unusual freedom of movement will be indulged in.

A further object of the invention is to provide, as a new and valuable article of manufacture, a garment readily convertible in structure, so far as engagement or disengagement and relative disposition of certain of its parts are concerned, at any portion or portions of the garment required or desirable for simple and practical transformation of the garment from one of the sportswear type to one of another type, and vice versa.

According to the present invention, as exemplified herein to constitute a man's shirt, a gusset element is formed for connection with and variable adjustment relative to the body of the garment; such connection being around the upper arm below the latter and from the front to the rear of the garment, with an upper attaching edge on the main body of the garment, and with a bottom attaching edge on the sleeve, whereby considerable expansion of material may be had underneath the armpit of the wearer at times when exceptionally great freedom of movement is desired. "Zipper" sections are stitched respectively along attaching edges of the gusset matchable with the edges of the main body of the garment and of the sleeve, whereby, when desired, the underneath portion of the sleeve can be drawn into the garment body in a manner such that the garment will then be given the customary appearance without excessive looseness being had in and adjacent the upper part

5 of the sleeve at times when the wearer is to be relatively inactive or wear an overgarment.

For further comprehension of the invention, and fuller appreciation of the objects, features and advantages thereof, reference will be had to the following description and accompanying drawing, and to the appended claim in which the various novel features of the invention are more particularly set forth.

10 In the accompanying drawing forming a material part of this disclosure:

Fig. 1 is a front elevational view of a garment pursuant to the invention, here embodied as a man's shirt; this view showing the garment with the "zippers" under the arms applied in a manner to effectuate concealment of the gusset at suitable times, so that the garment is then worn in perfect comfort although now appearing as it should, that is, to present the appearance of an ordinarily more or less formal wear garment, when little or no unusual activity is expected to be exercised by the wearer.

15 Fig. 2 is a rear elevational view of said garment, with the "zippers" drawn up as and for the purposes just above mentioned.

20 Fig. 3 is an enlarged fragmentary front elevational view of the garment, showing particularly the arrangement between the main body of the garment and an adjacent sleeve, and also showing more clearly that the direction of drawing up of the "zippers" is, as is now preferred, from the rear to the front of the garment; this view further showing, by broken-line delineation, the 25 crease or fold exhibiting itself along the length of the gusset when the latter is concealed by being completely housed in collapsed condition within the garment, as for more or less formal wear of the latter.

30 Fig. 4 is a similar fragmentary front elevational view of the same garment but now with the "zipper" opened and consequently with the gusset freed to expand and so permit greater freedom of movement of the sleeve relative to the garment body.

35 Fig. 5 is a plan view of the gusset removed from its connection with the garment.

40 Fig. 6 is a cross sectional view, taken along the line 6—6 of Fig. 4, looking in the direction of the arrows.

45 Referring now to the drawings in particular detail, 10 represents a garment in the form of a man's shirt, and comprising a main body part 11 having a front opening 12 and a collar 13, right and left sleeves 14 and 15 connected directly to the main body of the garment at the

upper shoulder, as indicated at 16 and 17. The curvilinearly cut lower back and lower front and armpit-underlying portions of the garment are connected at times when great freedom of movement is wanted of the garment, by a gusset 18 foldable along a line 19 (Fig. 5). This gusset, having curvilinear sides, tapers off at its ends, as indicated at 21, so that after its marginal portions have been connected to the main body of the garment and the sleeve, there is little play around the shoulders near the top of the latter as compared to the play which is permitted by the gusset including, and hence wide, portion of the garment adjacent the armpit.

Along the periphery 23 of the gusset and where it is connected with the garment body and with the sleeve, there is respectively sewed into place with the sleeve and with the gusset a "zipper" section 24, and into place with the main body of the garment and with the gusset a divided "zipper" section 25. At times, when great freedom of movement is not wanted or needed under the armpit, a "zipper" slide 26 is drawn from the rear of the garment around and under the armpit and to the front thereof, thereby closing in the gusset and causing it to fold along substantially its longitudinal center line. Such line may be predisposed to constitute a self-creating line of fold by arranging along said line, preferably before the gusset is connected with the sleeve and with the main body of the garment, a length of elastic applied in the form of stitches.

While I have illustrated and described the preferred embodiments of my invention, it is to be understood that I do not limit myself to the precise constructions herein disclosed and the right is reserved to all changes and modifica-

tions coming within the scope of the invention as defined in the appended claim.

Having thus described my invention, what I claim as new, and desire to secure by United States Letters Patent, is:

An upper garment having a body part and arm enclosing sleeves on the opposite sides thereof, each sleeve having a fixed connection with the side of the body part and an underarm gusset 10 approximately oval in shape secured at its outer edges to the body part and the sleeve and providing a flexible joint under the sleeve for the same, a row of slide fastener hooks secured to the one outer edge of the gusset, a row of mating slide fastener hooks secured to the other outer edge of the gusset, and a slide fastener closure engaged with hooks of both rows to couple and uncouple the rows of hooks, the gusset having a 15 fold line midway of its outer edges, and the slide fastener connecting each sleeve to said body part so that the sleeve will have a limited upward and outward movement when the rows of hooks are fully coupled on each other and allowing said gusset to increase said freedom of movement 20 when said hooks are fully uncoupled on each other.
